SEWING MACHINE FEED MECHANISMS

Carlton R. Hosley, Beverly, Mass., assignor to United Shoe Machinery Corporation, Flemington, N. J., a corporation of New Jersey

Application November 15, 1954, Serial No. 468,718

6 Claims. (Cl. 112—48)

The present invention relates to curved hook needle lockstitch sewing machines and primarily to improvements in feed mechanisms for shoe outsole stitching machines. As hereinafter described, the invention is disclosed as embodied in an outsole stitching machine similar to that identified in United States Letters Patent No. 473,870, granted April 26, 1892, to French and Meyer.

In the machine of the prior patent the work is fed by a work penetrating awl mounted for oscillation on a slide shifted in the direction of work feed by suitable cam actuated mechanisms. The awl is arranged to penetrate the work a stitch length in advance of the needle and is shifted into line with the needle path before retracting from the work. Unless the awl moves with precision into line with the needle path, the needle forms a perforation of its own leaving the awl hole unfilled with thread. As a result the completed seam is unsightly and unnecessarily weakened. If the awl moves exactly into line with the needle path, the needle will pass through the perforation formed by the awl so that these difficulties are avoided.

In the patented machine the awl is mounted on a stud separated from but aligned with one on which the needle is mounted, the awl stud being secured to a feed slide. After long use the engaging surfaces of the slide and a guideway in which it moves become worn and permit looseness to an extent that the awl in feeding the work fails to come into exact line with the needle path. This difficulty is aggravated while sewing thick heavy shoe soles, requiring heavy forces to be applied to the awl both during its penetrating stroke and its work feeding movements. Prevention of this difficulty cannot be accomplished simply by increasing the size of the bearing surfaces on the parts for the reason that the weight of the parts must be kept to a minimum where commercial sewing speeds are attained and the space about the sewing point must be kept clear of bulky projections to avoid interfering with the proper presentation of the shoe to the machine.

Numerous expedients have been devised for reducing or correcting misalignment of the awl with the needle path in the prior machine, such as the insertion of accurately graded gibs between the guideway and the feed slide for crowding the slide laterally in the guideway or the elimination of the feed slide and guideway entirely, as in United States Letters Patent No. 2,328,011 granted August 31, 1943, on application of Otto R. Haas and the use of a common mounting for the needle and awl on a single supporting stud. When the looseness from wear is taken up by inserting gibs between the feed slide and its guideway the position of the slide may be shifted sufficiently to impair the alignment of the awl with the needle path permanently. Misalignment of the awl with the needle path is increased still further, if in taking up the looseness it has been necessary to straighten the wearing surfaces by milling or grinding these surfaces.

In the machine of the Haas patent a complicated and expensive feed mechanism for actuating the awl along a

common mounting stud for both the needle and awl is substituted for the feed slide mechanism in the prior machine. The Haas feed mechanism also requires the use of a new cam as well as new levers and links to transmit motion to the awl segment, the mechanism prior to that of the Haas patent acting directly on the feed slide, while in the Haas machine a lever in the feed mechanism requires the use of a cam having the shape of its groove reversed.

An object of the present invention is to improve a shoe outsole sewing machine provided with a feed slide similar to that of the patent to French and Meyer, in a manner which will enable looseness from wear in the bearing surfaces of the slide and in its guideway to be taken up conveniently and effectively without throwing the awl in its fully fed position out of alignment with the needle path.

Another object of the invention is to provide in a shoe outsole sewing machine of the French and Meyer type, a feed mechanism of unusual durability, ease of adjustment, assembly and disassembly and effectiveness in operation, requiring relatively few changes in construction which are capable of being made without the exercise of unusual mechanical skill or complicated machine work.

To this end and as a feature of the invention, there is provided a shoe outsole sewing machine having a main frame carrying stitch forming and work feeding devices, including a curved hook needle and a curved work penetrating awl, an awl supporting segment formed with a grooved hub, a single needle and awl supporting stud fixed at one end in the machine frame and arranged to pass loosely through the hub of the awl segment, a guideway of a right angular cross section in the frame and a feed slide fitting the guideway for imparting movement to the awl supporting segment by means of a connecting yoke between the slide and the segment, the yoke having straight arms extending parallel to one of the surfaces of the slide and which enter the groove in the segment hub. With this construction looseness between the slide and guideway along the wearing surfaces which extend at right angles to the yoke arms may be taken up by crowding the slide in the guideway parallel to the direction in which the yoke arms extend, without changing the relative effective motion-transmitting position of the yoke arms in the groove of the awl segment hub, the parts close to the sewing point being kept within minimum dimensions to avoid interfering with a shoe being sewn.

In the preferred form of this feature, looseness between the slide and the guideway along their wearing surfaces which extend parallel to the yoke arms may be taken up, also without disturbing a close fitting relationship between the yoke and the groove of the hub segment by providing a slot and clamp screw joint between the yoke and slide, the slot extending at right angles to the yoke arms. Thus, two-wear adjustments may be made independently of each other by crowding the feed slide laterally in its guideway in two directions at right angles to each other without requiring the dimensions of the yoke or the hub to be increased to such an extent as to interfere with the presentation of a shoe to the stitch forming devices in the machine and without disturbing the alignment of the awl with the needle path.

The manner of adjustment also is simplified and improved with the use of clearly understood mechanical principles, thus avoiding the necessity of making a series of difficult time-consuming changes before a final result of the desired precision may be reached. For preventing displacement of the awl supporting end of the

stud in the preferred form of this feature, a readily removable brace engages the free end of the stud and is secured to at least two fixed parts of the machine separated from each other sufficient distances to insure essential rigidity.

These and other features of the invention relating to certain constructions, combinations and arrangements of parts, as hereinafter described and claimed, will be apparent from the following detailed specification taken in connection with the accompanying drawings, in which

Fig. 1 is a front elevation of a portion of the sewing head in a curved hook needle machine embodying the several features of the present invention;

Fig. 2 is a right side elevation of the portion of the machine shown in Fig. 1;

Fig. 3 is a perspective exploded view, looking from the right front, with parts broken away, of the work feeding mechanism in the machine; and

Fig. 4 is a similar perspective view showing an alternative form of stud brace employed in the machine, certain parts having been omitted.

The illustrated machine has a curved hook needle and a curved awl and is intended for use in sewing relatively thick hard outsoles to shoes, in which a projecting edge of the sole and other parts are formed with continually changing curvatures. To enable turning a shoe freely while sewing the curved edges of the shoe parts the devices engaging them are made as narrow as possible along the line of the seam consistent with effective sewing operations. Also, wide clearance spaces at either side of the sewing point are required.

During sewing operations the projecting parts are first penetrated by the awl and then are moved by the awl a stitch length to bring the awl perforation into the path of the needle, the needle entering the awl perforation to receive a loop of thread which is drawn through the work and presented to a shuttle carrying a supply of locking thread.

As the shoe is fed the projecting parts are pressed so strongly against the engaging surfaces in the machine that heavy forces of reaction frequently are applied to the needle and awl tending to deflect them and displace the shoe from proper sewing position. To offset the forces tending to deflect the needle and awl, their mountings are constructed as heavily as possible within the limits of the available space.

Referring to the drawings, the machine has a main frame 2 in which there is journaled a main sewing shaft 4 carrying cams 6, 8 and 10 for operating the stitch forming, work supporting and feeding devices. The stitch forming devices include the curved hook needle, indicated at 12, fixed in a segment 14 mounted for oscillation about a stud 16. The stud is secured at its left end in a projecting portion of the machine frame and passes loosely through the needle segment. To oscillate the needle toward and from the work, teeth on the needle segment are engaged by corresponding teeth on a cam actuated lever 18. The needle segment is prevented from movement lengthwise along the stud by a collar 20 which retains the needle segment in contact with a needle guide 22 supported loosely thereon and, in turn, engaged with the portion of the frame 2, in which the stud 16 is secured.

The awl is indicated at 24 and is fixed in a segment 26 also mounted for oscillation on the stud 16 which forms a common mounting for both the needle and awl, as in the machine of the patent to Haas. For oscillating the awl toward and from the work, teeth on the awl segment engage those on a cam actuated lever 28 which are of sufficient length to enable the awl to have imparted to it a work feeding movement. The hub of the awl segment also is similar to that of the Haas machine and has a peripheral groove 30 (Fig. 3) to receive an operative connection, to be described more fully hereinafter by which the awl may be moved along the com-

mon stud 16 into and out of alignment with the path of the needle.

To clamp the projecting shoe parts at the point of operation of the stitch forming devices, the parts are engaged by a work support 31 secured to the machine frame and by a presser foot 32 secured to a lever 34 fulcrumed on a pin 36 fixed in the machine frame. Cooperating with the needle in forming stitches are a loop spreader 37 and a shuttle 38. The loop spreader is secured to a cam actuated lever 40 fulcrumed on a stud 42 fixed in the machine frame. As thus far described, the illustrated machine is generally of the same construction and mode of operation as that disclosed in the French and Meyer patent or in the Haas 15 patent.

The work feeding movement is imparted to the awl in the French and Meyer patent by mounting the awl on a stud separate from that which supports the needle and moving the awl and its stud bodily toward and from the 20 needle. For this purpose the awl stud is secured directly in an upstanding arm of a feed slide mounted in a guideway on the machine frame several inches below the sewing point. The feed slide guideway of the French and Meyer patent is of adequate proportions to resist the forces of 25 reaction applied to the awl in feeding work and enables the awl while engaging the work to be moved with precision into line with the path of the needle so that the needle as it moves toward the work enters exactly into the 30 perforation in the work formed by the awl. After long use of the French and Meyer machine, the wearing surfaces of the feed slide and its guideway becomes so abraded that the awl no longer is brought uniformly into line with the needle path at the end of its work feeding movement. To overcome this difficulty it is customary to provide some means of taking up the looseness resulting from 35 wear in the guideway. Usually an adjusting means for the feed slide is provided and arranged to crowd the slide to one side in the guideway in either of two directions at right angles to the wearing surfaces, so that the slide is 40 guided uniformly in a straight line movement. In crowding the feed slide against its guideway, however, the awl stud is displaced from alignment with the needle path and the awl no longer can be brought into exact line with it.

In the illustrated machine the feed slide is indicated at 44 and the guideway, indicated at 46, on the frame 2 is 45 parallel to the common needle and awl stud. The wearing surfaces of the slide and its guideway are disposed in right angular relation to each other and to prevent displacement of the slide the guideway has screwed to it a pair of 50 parallel retainer plates 47.

The means for taking up the looseness from wear between the surfaces of the slide and guideway consist of a number of gibs 48, 50 and 52, the gib 48 acting on one 55 side surface of the slide 44 to crowd it rearwardly in the guideway and the gibs 50 and 52 acting on upper surfaces of the slide to crowd it downwardly against the lower horizontal surface of the guideway. For convenience of adjustment the plates 47 and the guideway have threaded 60 into them abutment screws 54 engaging the gibs at their inner ends.

If the awl is supported on a separate stud secured to an upwardly extending arm of the slide, as in the French and Meyer machine, then by changing the position of the gibs 48, 50 and 52 the axis of the awl stud will be displaced 65 from proper alignment with the needle stud, so that the awl cannot move into line with the path of the needle. If an attempt is made to employ a common needle and awl supporting stud, as in the Haas machine, and to actuate the awl segment by an nonadjustable connection with the feed slide, the stud and awl segment will be subject to excessive stresses after looseness from wear has occurred between the slide and its guideway. Furthermore, with the use of a common stud, after looseness has occurred there 70 is no method of preventing application of excessive bind-

ing stresses to the awl segment and stud, short of a major rebuilding operation.

To enable proper alignment of the awl with the needle path to be made conveniently and effectively in the machine of the present invention, regardless of the extent to which wear adjustments are required to take up looseness between the surfaces of the feed slide in its guideway, an upwardly extending arm of the slide has secured to it a forked yoke 56 which connects it with the awl segment. The yoke is constructed with a pair of rectangular vertical arms 60 fitting closely within the groove in the awl segment hub and extending parallel to the side surfaces of the slide. The yoke arms are of minimum dimensions to provide adequate strength and to fit snugly in embracing relation with the inner surface of the groove in the awl segment hub so that there is little if any clearance between them and the hub. By arranging the arms of the yoke in this manner displacement of the slide in its guideway while tightening the abutment screws 54 in the plates 47 in a direction to crowd the slide downwardly, is compensated for without adjustments by relative movement in a vertical direction between the yoke and the hub of the awl segment, this movement being taken up by the arms sliding in the groove of the awl hub so that no stress is applied to the awl segment or stud. To take up the horizontal looseness of the slide 44 in the guideway 42 the abutment screws 54 on the front side of the guideway are tightened, crowding the slide to the rear. To prevent one of the arms on the yoke 56 from being pressed forcibly against the inner surface of the groove 30 in the hub of the awl segment a simple horizontal adjustment is provided between the yoke and the slide.

To adjust the yoke 56 horizontally on the feed slide 44 the yoke and slide are connected by a slot and clamp screw joint. The upwardly extending arm on the slide which supports the yoke has formed in it an elongated horizontal slot 62. It will be apparent that this slot extends parallel with the upper and lower wearing surfaces of the slide and guideway and at right angles to the surface of the slide which is parallel to the inner surfaces of the arms 60. The slot has passing through it a clamp screw 64 threaded into the lower end of the yoke and arranged to secure the yoke adjustably to the slide. To prevent rotation of the yoke about the clamp screw 64 the flat lower end of the yoke engages a guide ledge 66 extending horizontally in exactly parallel relation to the upper and lower surfaces of the slide and guideway. If the screw 64 is loosened before the horizontal looseness is taken up between the slide and guideway, the yoke is free to adjust its position automatically on the slide as the looseness between the slide and guideway is taken up. Thereafter the screw 64 may be retightened and the parts reclamped. Thus, it is possible to take up the looseness of the slide in its guideway in two directions without causing excessive stress or friction to be impressed on the parts and the freedom from looseness will be restored to the feeding mechanism to bring it into its originally manufactured effectiveness.

To insure that the free right end of the common mounting stud 16 for the needle and awl will not be displaced by reactions of awl penetration and feeding movement of the work, a rigid three-armed brace 68 engages that end of the stud and is made fast to separated, fixed points on the machine. To support the brace 68 the presser foot pin 36 and the thread lifter stud 42 have extensions to the right beyond the machine frame which are engaged by split clamp portions of the brace. Between its clamp portions the brace has an arm formed with a perforation fitting snugly about the stud 16.

Another form of brace is indicated at 70 in Fig. 4. The brace 70 has screws 72 at its lower end passing through it and into threaded engagement with the rearward retainer plate 47. Between its ends the brace has a rearwardly extending lug through which passes a bolt 74 engaging a fixed portion of the machine frame 2. At its upper end the brace 70 is provided with a perforation

fitting the right end of the stud 16. The arrangement with either form of brace produces the same effective results and affords a construction which is easily assembled or dismantled.

With the construction of the present invention it is possible to keep the parts surrounding the sewing point of the machine within minimum dimensions, suitable clearance spaces being provided at either end of the needle and awl stud while affording adequate strength of the parts to resist the forces of action and reaction encountered during sewing operation maintained at least equal to or increased over the constructions of the prior patents. Thus, the arms of the forked yoke 56 are close together and the forked portion embraces the hub of the awl segment with a steady action on the inner surface of the groove 30 without requiring any enlargement of the hub for greater strength. It is possible to take up the vertical looseness between the slide and the guideway without making any other adjustment in the machine. The only adjustment required to compensate for change of position of the slide in the guideway when taking up the looseness in a horizontal direction is accomplished by loosening the clamp screw 64. When the clamp screw is loosened the yoke may be shifted horizontally while maintaining its angular position about the clamp screw.

The nature and scope of the invention having been indicated and a particular embodiment having been described, what is claimed is:

1. A shoe outsole sewing machine having a main frame, stitch forming and work feeding devices including a curved work penetrating instrument, a segment having a peripherally grooved hub for supporting said instrument, a stud fixed in the frame of the machine and passing loosely through the hub of the segment, a guideway of right angular cross section in the frame of the machine with wearing surfaces extending in parallel relation to the fixed stud, a feed slide fitting the guideway for imparting movement to the instrument supporting segment lengthwise of said stud, and means for taking up the looseness from wear by crowding the slide in either of two directions at right angles to the wearing surfaces of the slide and guideway, in combination with a connecting yoke between the slide and the segment, provided with a rectangular arm entering the groove in the segment hub and extending parallel to one of the wearing surfaces on the slide.

2. A shoe outsole sewing machine having a main frame, stitch forming and work feeding devices including a curved work penetrating instrument, a segment having a peripherally grooved hub for supporting said instrument, a stud fixed in the frame of the machine and passing loosely through the hub of the segment, a guideway of right angular cross section in the frame of the machine with wearing surfaces extending in parallel relation to the fixed stud, a feed slide fitting the guideway for imparting movement to the instrument supporting segment lengthwise of said stud, means for taking up the looseness from wear by crowding the slide in either of two directions at right angles to the wearing surfaces of the slide and guideway, in combination with a connecting yoke between the slide and the segment, provided with a rectangular arm entering the groove in the segment hub and extending parallel to one of the wearing surfaces on the slide, and means for securing the yoke to the slide comprising a slot and clamp screw joint, the slot of which extends at right angles to the wearing surface on the slide which is parallel to the arm to enable adjustment to be made in the position of the yoke on the slide in compensation for a change in position of the slide caused by taking up the looseness of the slide in the guideway.

3. A shoe outsole sewing machine having a main frame, stitch forming and work feeding devices including a curved work penetrating instrument, a segment having a peripherally grooved hub for supporting said instru-

ment, a stud fixed in the frame of the machine and passing loosely through the hub of the segment, a guideway of right angular cross section in the frame of the machine with wearing surfaces extending in parallel relation to the fixed stud, a feed slide fitting the guideway for imparting movement to the instrument supporting segment lengthwise of said stud, means for taking up the looseness from wear by crowding the slide in either of two directions at right angles to the wearing surfaces of the slide and guideway, in combination with a connecting yoke between the slide and the segment, provided with a rectangular arm entering the groove in the segment hub and extending parallel to one of the wearing surfaces on the slide, means for securing the yoke to the slide comprising a slot and clamp screw joint, the slot of which extends at right angles to the wearing surface on the slide which is parallel to the arm to enable adjustment to be made in the position of the yoke on the slide in compensation for a change in position of the slide caused by taking up the looseness of the slide in the guideway, and a guide ledge on the slide engageable with the yoke and extending parallel to the slot to prevent rotation of the yoke about the clamp bolt.

4. A shoe outsole sewing machine having a main frame, stitch forming and work feeding devices comprising a curved hook needle and a curved awl, needle and awl supporting segments, a common stud passing through the segments and having one end fixed in the frame of the machine, the awl supporting segment having a peripherally grooved hub, a guideway in the frame formed with wearing surfaces extending in a direction parallel to the axis of the stud, a feed slide mounted in the guideway, and means for taking up the looseness between the wearing surfaces of the guideway and feed slide, in combination with a groove entering yoke on the slide embracing the hub of the segment and a removable brace secured to the other end of the stud and to two separated, fixed portions of the machine.

5. A shoe outsole sewing machine having a main frame, stitch forming and work feeding devices com-

prising a curved hook needle and a curved awl, needle and awl supporting segments, the awl supporting segment having a peripherally grooved hub, a common stud passing through the needle and awl segments and having one of its ends fixed in the frame, a work support on the frame, a presser foot acting with the work support to clamp the work at the point of operation of the stitch forming devices, a fulcrum pin in the frame about which the presser foot moves toward and from the work support, a thread lifter, a fulcrum stud in the frame about which the thread lifter moves and a removable brace engaging the common needle and awl stud, the presser foot pin and the thread lifter stud.

6. A shoe outsole sewing machine having a main frame, stitch forming and work feeding devices including a curved work penetrating instrument, a segment having a peripherally grooved hub for supporting said instrument, a stud having at one end fixed in the frame of the machine and passing loosely through the hub of the segment, a guideway of right angular cross section in the frame of the machine with wearing surfaces extending in parallel relation to the fixed stud, a feed slide fitting the guideway for imparting movement to the instrument supporting segment lengthwise of said stud, and a retaining plate on the guideway to prevent lateral movement of the slide therein, in combination with a connecting yoke between the slide and the segment entering the groove in the segment hub, and a brace removably secured at separated points to the retaining plate on the guideway and the main frame and engaged with the other end of the said stud.
